CANOPY SHELTER SUPPORT

Ralph B. Feffer, Jr., 3100 S. 7th St., Phoenix, Ariz.

Filed July 13, 1959, Ser. No. 56,748

Term of patent 14 years

(Cl. D13—1)

FIG. 2

FIG. 1

FIG. 6

FIG. 3

FIG. 4

I claim:

The ornamental design for a canopy shelter support, as shown.
